UNITED STATES PATENT OFFICE.

SIMPSON J. ROUTLEDGE, OF ENSLEY, ALABAMA.

SAFETY ANGLE-BAR.

980,009.

Specification of Letters Patent. Patented Dec. 27, 1910.

Application filed March 18, 1910. Serial No. 550,142.

To all whom it may concern:

Be it known that I, SIMPSON J. ROUTLEDGE, a citizen of the United States, residing at Ensley, in the county of Jefferson and 5 State of Alabama, have invented new and useful Improvements in Safety Angle-Bars, of which the following is a specification.

This invention relates to an angle bar for railroad joints.

10 The object of the invention is to provide an angle bar adapted to be used in connection with an ordinary fish plate, the said angle bar being provided with a detachable key member which is adapted to serve as a 15 securing means for the nuts of the connecting bolts, and embodies other novel features of construction which will be hereinafter fully set forth.

With the above objects in view, the invention 20 resides in the novel construction and combination of parts hereinafter fully described and claimed.

25 In the accompanying drawings there has been illustrated a simple and preferred embodiment of the improvement and in which drawings:—

Figure 1 is a perspective view of the meeting ends of a pair of railway rails provided with my improvement. Fig. 2 is a transverse sectional view upon the line 2—2 of 30 Fig. 1.

In the accompanying drawings, the numeral 1 designates the meeting ends of a pair of railway rails. These rails 1 are of 35 the ordinary construction, comprising a head 2, base flanges 3 and connecting web 4. Each of the rails has its web provided with a plurality of openings, the same being adapted for the reception of securing bolts 5 40 having the ordinary retaining nuts 6.

The numeral 7 designates a fish plate of the ordinary construction which is positioned adjacent to the webs of the rails upon 45 one side thereof and which is adapted to receive the head portions of the bolts 5. Positioned upon the opposite sides of the rails is my improved angle bar 8. This bar 8 comprises a horizontal straight portion or base 9 and an integrally formed vertical member 10. The vertical member 10 is provided with a plurality of openings coinciding 50 with the openings of the webs of the rails and of the fish plates, the said openings being adapted for the reception of the threaded portions of the bolts 5. The base 9 of the angle bar has its outer edge pro-

vided with an integrally formed longitudinally extending undercut lip 11, the same having its inner wall or edge 12 beveled or inclined downwardly toward the outer edge 60 of the said base member 9. The lip 11 is provided with a plurality of notches 13 upon its inner edge, and its notches are adapted to align with suitable openings 14 provided in the base member 9. The vertical portion 65 10 of the angle bar 8 is adapted to engage with the webs of the rails and the base member 9 is adapted to overlie the base flanges 3 of the rails. The base flanges 3 are provided with openings 15, the same aligning with the 70 openings 14 and notches 13 of the angle bar 8.

The numeral 16 designates the key of the angle bar. This key 16 comprises a longitudinal member of a length corresponding 75 to the length of the angle bar 8, and the said key has one of its faces inclined or beveled as at 17 to correspond with the inclined wall 12 of the overlying lip 11. The top wall of the key 16 is also slightly beveled 80 toward its opposite edge as indicated by the numeral 18. The beveled or inclined portion 17 of the key 16 is provided with suitable notches 19, the same being adapted to align with the notches 13 provided in the 85 overlying lip 11 and the openings 14 in the base portion of the angle bar.

Briefly stated the method of connecting the key to the angle bar is as follows:— The nuts 6 are screwed home upon the bolts 90 5 and the key 16 is positioned adjacent one end of the base 9, its inclined edge 17 being in alignment with the inclined wall 12 of the lip 11. A suitable implement such as a 95 hammer is employed to force the key upon the base and beneath the nuts 6. The inclined upper wall 18 of the said key engages the nuts causing the same to revolve until their under faces assume a substantially horizontal position. When the key 100 has been driven its full length so that its notches 19 align with the notches 13 of the overlying lip 11, suitable spikes 20 are inserted within the openings provided by the 105 said notches and the openings 14 of the angle bar as well as the openings 15 of the base flanges of the rails.

Having thus described the invention, what is claimed as new is:—

In combination with the meeting ends of 110 a pair of rails, a base plate having bolts and nuts therefor, of an angle bar, said

angle bar having its horizontal straight base portion provided with an undercut lip upon its outer edge, the inner wall of the said lip being inclined, the inner edge of the lip being provided with a plurality of cut-away portions, the base of the angle bar having openings alining with the said cut-away portion, a key for the angle bar, said key comprising a rectangular member having one of its edges beveled and provided with cut-

away portions adapted to aline with the cut-away portions of the lip, the top of the key member being inclined, all substantially as and for the purpose set forth.

In testimony whereof I affix my signature 15 in presence of two witnesses.

SIMPSON J. ROUTLEDGE.
